UNITED STATES PATENT OFFICE.

FREDERICK A. WIDMER, OF CORSICANA, TEXAS.

COLLAPSIBLE ROTARY WELL DRILL.

Application filed January 9, 1922. Serial No. 528,046.

To all whom it may concern:

Be it known that I, FREDERICK A. WIDMER, a citizen of the United States, residing at Corsicana, in the county of Navarro and State of Texas, have invented certain new and useful Improvements in Collapsible Rotary Well Drills, of which the following is a specification.

This invention relates to improvements in bits for well drilling and it pertains more particularly to a bit of this character designed for use in drilling wells by the rotary drill system.

In the rotary system of drilling wells the well drilling bits are screwed onto the well casing or drill pipe which is rotated and the bits cut through the rock or hard strata and when necessary to remove the bits for sharpening the drill pipe must be taken out of the well. To obviate this removal of the drill pipe I have devised a well drilling bit of collapsible form which may be locked to the end of the drill pipe and so constructed and arranged that the bits can be detached 25 or unlocked and removed from the drill pipe for the purpose of repairs or sharpening without removing the drill pipe or casing. Further, the bits are constructed with as few parts as practically possible consistent with strength, durability and practical 30 use and manufacture.

The invention will be more fully understood by reference to the following description, taken in connection with the accompanying drawings, forming part hereof, in which—

Figure 1 is an elevational view, partly in longitudinal section, of a portion of a drill pipe embodying the invention and showing the improved collapsible bits in position 40 therein.

Figure 2 is an enlarged detail longitudinal sectional view of the drill pipe taken lower down and showing the connection of the drill bits and drill shank and locking means with the bits in operative position.

Figure 3 is a cross-sectional view taken on line 3—3 of Figure 2.

Figure 4 is an elevational view of a tubular member or section of pipe screwed onto the plunger, with bail for attaching to a cable for removing the bit, the pipe or tubular member in broken formation and partially sectioned.

Figure 5 is an elevational view of the lower end of the device, the bits removed.

Figure 6 is a detail view in side elevation of one of the keys for locking the bits in position.

Figure 7 is a longitudinal sectional view 60 of the device with part broken away and illustrating the bits in collapsed position, for removal from the drill pipe.

Figure 8 is a partial longitudinal sectional view taken on the line 8—8 of Figure 2. 65

Figure 9 is a side elevational view, illustrating in detail one of the bits, and

Figure 10 is a cross-sectional view taken on the line 10—10 of Figure 8.

Referring more in detail to the drawings, 70 1 denotes the lower end of a drill pipe the inside diameter of which is enlarged as shown in Figures 2, 7 and 8 for the insertion of an end member or nose 2 which is screwed therein. The nose 2 is hollowed 75 down to a point 3 beyond which it is slotted as at 4, see Figure 5, for allowing the bits to be projected therethrough. The nose is also slightly conical.

A bit shank 6 is hollowed at 7 down to a 80 shoulder 8 upon which rests a spring 9 and is provided with a nut 6^a for the upper part of the spring. The lower end of the shank 6 is slotted as will be seen by reference to Figure 8 for the drill bits 10—10, and providing also a recess 10^a for the locking keys 11—11 one of which is shown in detail in Figure 6. These keys have slots 11^a and are supported by the pins 11^b each key having two slots with the keys overlapping each other as illustrated in Figure 3. 85 90

The bits 10—10 are arranged to lie one against the other and are relatively flat, each upper end of the bits being provided with a slotted aperture 12 so that the bits 95 may be suspended upon and removed from a pin 13 in the shank 6 when desired. The inner faces of these bits, likewise the nose 2, are provided with channels or ports 14 for the circulation of water through the 100 drill pipe. Figure 2 illustrates the bits in operative position and in Figure 7 the bits are shown in collapsed position.

Within the shank 6 is a plunger 15 with a wedge-shaped end 16 by means of which 105 the keys 11—11 are moved apart, the wedge passing between the keys. 17 is a bushing closing the upper end of the tubular shank 6 and centralizing the plunger therein.

Screw-threaded upon the upper end of 110 the plunger 15 is a tubular member 17' which may be of several sections of pipe

and which has a bail 18 by means of which the plunger, bits and shank are removed from the well.

In practical operation the nose 2 is 5 screwed onto the lower end of the drill pipe section and the member 17', to which is attached the plunger, and bit shanks 6-6, carrying the bits 10-10, are inserted into the pipe 1.

10 In normal position the keys 11-11 are spaced apart as shown in Figure 7 with the end of the plunger therebetween. The weight of the plunger and parts will cause the wedge-shaped end 16 of the plunger to 15 force the keys downward until the shoulders thereof, 16^b, have passed into the recess 10^a, whereupon the keys will be forced further apart and the plunger will move upon and against the bits and force them 20 outward into the position depicted in Figure 2. The object of the spring 9 is to provide a cushion so that the plunger will not fall too heavily and also as an aid in retracting the bits when removing. This is 25 done by inserting the cable or sand line into the drill pipe or casing and attaching it to the bail 18. An upward pull will release the keys from the recess 10^a, collapse the bits and permit them to pass upward, without 30 the necessity of removing the casing or drill pipe.

What is claimed is—

1. A drilling bit for rotary well drilling, in combination with the drill pipe, comprising a hollowed shank member to which the bits are removably attached, a plunger carried in the hollowed shank, a spring on the

plunger, means for connecting the plunger to a cable, keys between the plunger and bits and so arranged that when the device is 40 lowered into the well the plunger and shank will move the keys downward and apart and cause them to spread the bits into operative position and lock them therein.

2. A drilling bit for rotary well boring 45 in combination with the drill pipe, comprising a shank within the drill pipe to which the bits are removably secured, a plunger within the shank, keys actuated by the plunger and shank and so arranged that 50 when the plunger and shank are pushed downward the keys will be shoved apart and against the bits to move them into operative position and locked by said keys.

3. A collapsible bit for rotary well drilling in combination with the drill pipe, comprising a shank member, bits removably secured thereto, a plunger having means for connection with the well cable and reciprocating within the shank, drill bits removably attached to the shank, a nose or end member secured to the end of the drill pipe and through which the bits project, slideable keys between the bits and plunger and a recess in the casing or drill pipe adjacent 65 the keys, said parts arranged so that the plunger and shank will collapse and extend the bits and said keys will lock and release them, when the bits are lowered into and removed from the well.

In testimony whereof I have signed my name to this specification.

FREDERICK A. WIDMER.
